Primary Examiner — Abraham Bahta(74) *Attorney, Agent, or Firm* — Hodgson Russ LLP(57) **CLAIM**

The ornamental design for a bassinet, as shown and described.

DESCRIPTION

FIG. 1 is a rear perspective view of a bassinet showing my new design in a first position;

FIG. 2 is a front elevational view of the bassinet of FIG. 1; FIG. 3 is a rear elevational view of the bassinet of FIG. 1; FIG. 4 is a left side elevational view of the bassinet of FIG. 1;

FIG. 5 is a right side elevational view of the bassinet of FIG. 1;

FIG. 6 is a top view of the bassinet of FIG. 1;

FIG. 7 is a bottom view of the bassinet of FIG. 1;

FIG. 8 is a front perspective view of the bassinet of FIG. 1 in a second position;

FIG. 9 is a front perspective view of the bassinet of FIG. 1 in a first position;

FIG. 10 is a front perspective view of a second embodiment of a bassinet showing my new design in a first position; and, FIG. 11 is a right side elevational view of the bassinet of FIG. 10.

The broken lines illustrate unclaimed features that form no part of the claimed design.
